(57) **CLAIM**

The ornamental design for a flashlight, as shown and described.

DESCRIPTION

FIG. 1 is a top view of the invention;
FIG. 2 is a side view of the invention, the other side being a mirror image thereof;

FIG. 3 is bottom view of the invention;

FIG. 4 is a front end view of the invention;

FIG. 5 is a rear end view of the invention;

FIG. 6 is a top view of a second embodiment of the invention;

FIG. 7 is a side view of the second embodiment of the invention, the other side being a mirror image thereof;

FIG. 8 is a bottom view of the second embodiment of the invention;

FIG. 9 is a front end view of the second embodiment of the invention;

FIG. 10 is a rear end view of the second embodiment of the invention;

FIG. 11 is a top view of a third embodiment of the invention;

FIG. 12 is a side view of the third embodiment of the invention, the other side being a mirror image thereof;

FIG. 13 is a bottom view of the third embodiment of the invention;

FIG. 14 is a front end view of the third embodiment of the invention;

FIG. 15 is a rear end view of the third embodiment of the invention;

FIG. 16 is a top view of a fourth embodiment of the invention;

FIG. 17 is a side view of the fourth embodiment of the invention, the other side being a mirror image thereof;

FIG. 18 is a bottom view of the fourth embodiment of the invention;

FIG. 19 is a front end view of the fourth embodiment of the invention; and,

FIG. 20 is a rear end view of the fourth embodiment of the invention.
